CRACKING BLENDED HEAVY CRUDES

Ralph M. Hill, Cranford, N. J., assignor to Standard Oil Development Company, a corporation of Delaware

Application November 13, 1939, Serial No. 303,985

2 Claims. (Cl. 196—50)

The present invention relates to improvements in the conversion of hydrocarbon oils, catalytically or thermally, to produce motor fuels of the gasoline type; and more particularly, this invention relates to improvements in which a gas oil, which normally is a high coke producing feed stock in the type of operation here in question, is blended with a recycled oil, such as a virgin or cracked gas oil which has lower coke forming tendencies, and subjected to a cracking operation, whereupon a gasoline of high octane number is produced, as well as a fuel oil of good quality, the amount of coke formed during the conversion being relatively small.

One object of the present invention is to carry out a catalytic cracking operation under conditions such that a good yield of gasoline is obtained from reduced crudes while, at the same time, a relatively small amount of coke is formed.

Another object of the present invention is to provide a method in which oil may be cracked catalytically, while obtaining a favorable product distribution.

To the accomplishment of the foregoing and related ends, I may first subject a crude oil to a topping operation and then subject the bottoms from this operation to a viscosity-breaking reaction. After that I combine the viscosity-broken product with a cycle stock, such as a gas oil which has lower coke forming tendencies than the viscosity-broken reduced crude, and then subject the mixture to a catalytic cracking operation.

Reference is had at this point to the accompanying drawing which shows diagrammatically, in partial vertical section, apparatus means for carrying the present invention into effect.

In the drawing, a feed, such as a reduced crude, is cracked in viscosity breaker 26 and is introduced into the cracking system from reservoir 1 through line 2 and at the same time a gas oil, which may have been produced in a cracking operation, may be discharged from reservoir 3 into line 4 and from there into mixing chamber 5, where it is admixed in suitable proportion with a viscosity-broken product from reservoir 1.

It will be understood that, as an obvious modification of the foregoing, the viscosity-breaking reactor 26 may be in direct communication with line 2 thus by-passing reservoir 1 and the product may retain substantially all of the heat content it acquired from the viscosity-breaking process. Also the gas oil in reservoir 3 may be a gas oil obtained by distillation from the original hydrocarbon feed stock.

The blend of viscosity-broken hydrocarbon oil

and gas oil is discharged from vessel 5 into line 6 and thence into a secondary bubble tower 17 where hydrocarbons boiling within the gasoline range are stripped from the said blend. The higher boiling hydrocarbons containing the blend are withdrawn through line 7, and after that, pumped through line 7a into heating coil 8, where it is vaporized. The vaporized material is discharged into line 10 and from there into the bottom of reaction chamber 11. The reaction chamber shown is of the tray type. This type of reactor may be provided according to known methods, with intake and discharge manifolds externally disposed and in communication with the reactor, which manifolds permit parallel flow of vapors through several beds of catalyst, i. e. the vapors may be permitted to flow into the reactor through several branch pipes leading from a common manifold and then flow upwardly or downwardly through the beds of catalyst C, supported on perforated trays and then issue from the reactor through several branch pipes into a common manifold pipe.

This manifolding means is not shown in the drawing. According to the drawing the vapors would flow serially through the several beds. Of course, it would also be possible to provide one continuous bed of catalyst in reactor 11.

From reactor 11, the vapors are discharged into line 12 and from there, into primary bubble tower 14. The bottoms from this tower are withdrawn through line 15 and caused to flow into line 1a for recycling purposes, or if this fraction becomes too refractory for further cracking, it may be withdrawn from the system through line 15a for use as a fuel oil. The overhead product from bubble tower 14 is discharged through line 16 into the previously mentioned secondary bubble tower 17, the gasoline vapors from this tower issuing through line 18, then passing through condenser 19, thence passing into receiving drum 20, the fixed gas being withdrawn through line 21 and the gasoline recovered through line 22.

Periodically the catalyst C in chamber 11 will require regeneration and for that purpose, the valves in lines 10 and 12 are closed and a purging gas is forced into the reactor through line 23 and withdrawn through line 24. This purging gas may be steam, flue gas, nitrogen or the like. After purging, a regeneration gas may be forced through the catalyst to burn off carbonaceous contaminants deposited thereon during cracking. This regeneration gas may be passed into the reactor through line 24 and the products of combustion withdrawn through line 23. The regen-

eration gas may be air diluted with flue gas, steam, N_2 or the like, to the extent that it contains about 1 to 10% free oxygen. If the catalyst is an acid treated clay, the temperature of the regeneration oxidation should not exceed about 1000° F. to 1100° F., but if a synthetic gel catalyst is employed, the regeneration may be carried out at a somewhat higher temperature, say 1200° F. The details of regeneration of a catalyst of this type are well known to the art. It may be said that two reactors such as 11 may be employed in the present process so that while one body of catalyst is "on stream," the other may be undergoing regeneration, thus affording continuous operation.

In order to give concrete examples of my invention, the following details are disclosed:

A Lago crude was distilled to remove gasoline, the residue having an A. P. I. gravity of 15.3°. This material was viscosity-broken under the following conditions:

The heated material was contacted with an acid treated clay catalyst which was maintained at a temperature of 774° F. at a feed rate of 1.2 volumes of reduced crude per volume of catalyst 25 per hour, the oil being measured on a cold oil basis.

The foregoing process yielded the following:

Wet gas	weight per cent	1.3
Gasoline	volume per cent	4.8
Material with lowest boiling of 400° F.	do	92.5
Coke	weight per cent	1.6

The material boiling at 400° F. and above had an A. P. I. gravity of 17.4 and a Furul viscosity at 35 122° F. of 28.0.

In order to show the advantage of employing the present process the following examples are given in the first of which the material derived from the viscosity-breaking operation boiling at and above 400° F. was catalytically cracked and in the second, the same material was mixed with a cracked gas oil of low coke forming propensities and then cracked.

Example 1

In this example the oil boiling at 400° F. and above was contacted with a bed of catalyst, the feed rate being 0.6 volume of oil per volume of catalyst per hour on a cold oil basis. The temperature in the reaction zone was 850° F. The catalyst employed was an acid treated clay. The catalyst was maintained at a temperature of 850° F. during the cracking operation. The process yielded:

Wet gas	per cent by weight	4.2
Gasoline	per cent by volume	23.2
Gas oil	do	64.5
Coke	per cent by weight	10.6

Example 2

In this experiment two parts by volume of the material boiling at and above 400° F. in the previous example was mixed with one part of a gas oil resulting from the catalytic cracking of an East Texas virgin gas oil in which the gas oil produced in the cracking process had low coke forming tendencies. The mixture was subjected to the following conditions:

The feed was contacted with an acid treated clay catalyst at a feed rate of 1.2 volumes of oil per volume of catalyst per hour. The catalyst

was maintained at a temperature of 903° F. The process yielded the following:

Wet gas	per cent by weight	6.1
Gasoline	per cent by volume	39.6
Gas oil	do	50.5
Coke	per cent by weight	8.8

The gravity of gas oil was 21.3 A. P. I.

It will be noted from the foregoing examples that the straight gas oil when cracked according to the process of Example 1 gave a conversion of 23.2% gasoline and 10.6% coke. When this gas oil was blended with the cracked gas oil, the conversion was 39.6% gasoline and 8.8% coke. It will thus be seen that less coke was produced in the process of Example 2 than in the Example 1 process in spite of the fact that in Example 2 a much higher gasoline conversion was obtained than in the run of Example 1. The temperature in the run of Example 2 was higher than the preceding run but this serves to emphasize more clearly the value of the present invention since it is well known that when cracking in a given phase, vapor or liquid, higher temperatures or higher gasoline conversions yield greater percentages of coke.

The precise details enumerated in the above examples obviously are not fixed and numerous modifications of the procedures of the examples may be made by those skilled in this art without departing from the spirit of the invention. For example, the ratio of gas oil or cycle oil that has a low coke forming tendency under cracking conditions to the gas oil having a relatively high coke forming tendency may vary from one half to four or five volumes of the former to one of the latter, depending on the nature of the high coke forming stock. The optimum ratio can be determined for any given stock by experiment in view of the foregoing disclosure. As to the catalyst, of course, any known cracking catalyst may be used, for instance, a silica-alumina synthetic gel, silica-magnesium compound or gel or the like. The cracking temperatures and pressures may be within conventional ranges. The octane number of the gasoline in a once-through operation is relatively high, say in the neighborhood of 75. The present process is applicable to cracking gas oils, heavy naphthas and may be advantageously carried out in the presence of hydrogen.

Having described my invention, what I claim is:

1. A method of converting higher boiling hydrocarbons into lower boiling hydrocarbons suitable for motor fuel which comprises heating a heavy residual oil to reduce its viscosity without extensive formation of motor fuel constituents, mixing the hot resulting viscosity-broken product with a cycle gas oil from a separate catalytic cracking process to supply heat thereto, fractionating the mixture to separate condensate oil higher boiling than about 400° F. from lower boiling constituents, the condensate oil containing constituents from the residual oil which have a relatively high coke-forming tendency and constituents from the cycle gas oil which have a relatively low coke-forming tendency, passing the condensate oil through a cracking zone maintained at active cracking temperature and containing a cracking catalyst, keeping the condensate oil within said cracking zone for a time sufficient to form a substantial amount of lower boiling hydrocarbons and thereafter fractionating the cracked products to separate a motor fuel fraction therefrom.

2. A method of converting higher boiling hydrocarbons into lower boiling hydrocarbons suitable for motor fuel which comprises mixing a feed stock having a relatively high coke-forming tendency when cracked with an oil having a relatively low coke-forming tendency when cracked, fractionating the mixture in a first fractionating zone in the presence of a light fraction produced in the process to separate a motor fuel fraction from higher boiling constituents, condensing the 10

motor fuel fraction, catalytically cracking the higher boiling constituents to form lower boiling hydrocarbons, fractionating the cracked products in a second fractionating zone to give a light fraction and a heavy fraction, recycling the heavy fraction to the catalytic cracking zone, and passing the light fraction to the said first fractionating zone.

RALPH M. HILL.
